FASTENING INSERTING MACHINE

Fred Ricks and Harold Ernest Elliott, Leicester, England, assignors to United Shoe Machinery Corporation, Paterson, N. J., a corporation of New Jersey

Application January 15, 1935, Serial No. 1,928
In Great Britain January 29, 1934

12 Claims.

(Cl. 1—29)

This invention relates to fastening forming and inserting machines and is herein shown, by way of illustration, embodied in a machine for severing and inserting wire slugs in the bottoms of boots and shoes of the type disclosed in United States Letters Patent No. 786,190, granted March 28, 1905, on an application filed in the name of Louis A. Casgrain.

In machines of the type referred to above it is sometimes desirable to eliminate the usual movement of translation of the wire severing and transferring member and to utilize in place thereof of a rotary movement. There is disclosed in United States Letters Patent No. 1,651,469, granted December 6, 1927 on an application filed in the name of William Thomas Buckingham Roberts, a mechanism which aligns the wire receiving passage in the severing and transferring member with a wire feeding passage prior to the severing operation. After the wire severing operation the member is rotated to position the passage in the member in alignment with the path of movement of a driver.

It is an object of the present invention to provide an improved mechanism applicable to such a machine for operating the wire severing and transferring member which will obviate the necessity of accurate adjustment of the fastening—severing and transferring member and which will insure proper alignment of the passage in said member with a wire receiving passage prior to the severing operation and with the path of movement of the driver after the transferring operation has been completed.

A feature of this invention, accordingly, consists in mechanism constructed and arranged to cause relative movement between a movable die and a stationary die, the mechanism including means for holding the dies positively against movement relatively to each other prior to the severing operation and to hold the transferring die positively against movement after it has been moved to inserting position. As illustrated, the machine is provided with a die carrier arranged for rotation to move a die from a substantially horizontal fastening receiving position to a substantially vertical fastening driving position. A link is connected at one end to the carrier and a bell crank lever having an arm connected to the other end of the link, the link and the arm being arranged in a straight line when the movable die is in fastening receiving position. The machine is also provided with a second link connected to the other arm of said bell crank lever. A second bell crank lever is connected to

the other arm of the second link, said last-mentioned link and arm being arranged in a straight line when the die carrier is in driving position. Each of the bell crank levers is provided with independent means for adjusting the position of the respective bell cranks to insure that the movable die will be properly aligned in fastening receiving position and in driving position.

These and other features of the invention will appear more fully from the following detailed description when read in connection with the accompanying drawings and will be pointed out in the accompanying claims.

In the drawings,

Fig. 1 is a view in front elevation of a mechanism embodying the present invention;

Fig. 2 is a view in side elevation of the mechanism shown in Fig. 1;

Fig. 3 is a view in left-hand elevation partly in section of means for adjusting a severing and transferring die of the mechanism relatively to a co-operating shearing die; and

Fig. 4 is a view in side elevation, partly in section, of means for adjusting the shearing and transferring die relatively to the path of movement of the fastening inserting instrumentalities of the machine.

In the illustrated embodiment of the invention the mechanism for severing and transferring fastenings into the path of movement of a driver 10 (Fig. 2) is shown as applied to a machine of the type disclosed in United States Letters Patent No. 1,651,469, granted December 6, 1927, on an application filed in the name of William Thomas Buckingham Roberts. The preferred form of mechanism comprises a severing and transferring member 12 which is arranged to be turned through 90° during each cycle of operation of the machine to cut off a length of wire and to transfer the severed wire to driving position. The member 12 is provided with a shearing die 14 and is supported on the forward end of a horizontal sleeve 16 which extends rearwardly.

The sleeve 16 is rotatably mounted on a shaft 18 fixed in the frame of the machine. The sleeve 16 has secured to its rear end a forked arm 20 provided with a crank pin 22. When the severing and transferring member 12 is in the position shown in Fig. 1 to receive the end of the wire to be cut off (hereinafter called the shearing position) the crank pin 22 is located at the right of the shaft 18 and the axis of the sleeve 16 and the pin 22 are substantially in the same horizontal plane. When the shearing and transferring member 12 has been turned to the position

indicated by dotted lines in Fig. 1 to sever a fastening and to transfer the fastening into the path of movement of the driver 10 the axis of the crank pin 22 is located directly above the axis of the sleeve 16 and in substantially the same vertical plane.

The crank pin 22 forms a pivotal connection between the forked arm 20 and one end of a link 24, the other end of which is pivotally secured to a depending arm 26 of a bell crank lever 28. The bell crank lever 28 is pivoted on an eccentric sleeve 30 which is rotatably mounted on a horizontal shaft 32 extending forwardly and rearwardly of the machine and lying directly above the sleeve 16 of the shearing and transferring device. The link 24 and the arm 26 of the bell crank lever 28 form in effect a toggle which is straightened when the shearing and transferring device 12 is in its shearing position, as shown in Fig. 1. The eccentric sleeve 30 is provided with a laterally extending arm 34 having formed therein a curved slot 36 concentric with the axis of the shaft 32 on which the sleeve 30 is mounted. The eccentric sleeve 30 may be adjusted about the shaft 32 by rotating the arm 34 when the toggle 24, 26 is in straightened condition to adjust the position of the shearing and transferring die 14 relatively to a co-operating shearing die 38 to aline the wire receiving passages 37 and 39 in the dies 14 and 38. The arm 34 is clamped in adjusted position by a screw 40 passing through the slot 36 in the arm 34 and threaded into a member 42 which is held in a fixed position and is supported at one end on an enlarged portion 44 of the eccentric sleeve 30. The enlarged portion 44 of the eccentric sleeve 30 is concentric with the shaft 32 so that rotation of the eccentric sleeve 30 does not cause displacement of the member 42.

A second arm 46 of the bell crank lever 28 is pivoted to a link 48 the other end of which is pivotally connected to an arm 50 of a bell crank lever 52. The bell crank lever 52 is pivoted on an eccentric portion 54 of a shaft 56 which is rotatably mounted in a bracket 58 secured to the machine frame by a screw 59. The shaft 56 which serves to support the other end of the member 42 is positioned to the right of the shaft 32 on which the eccentric sleeve 30 is mounted and its axis is in substantially the same horizontal plane as the axis of the shaft 32. The arm 50 on the bell crank lever 52 and the link 48 form in effect a second toggle which is in straightened position, as shown in its dotted line position in Fig. 1, when the shearing and transferring device 12 is in fastening inserting position. The shaft 56 is provided with a laterally extending arm 60 by which the shaft 56 and the eccentric 54 may be rotated. By adjusting the eccentric 54 when the toggle 48, 50 is in the straightened position mentioned above, the shearing and transferring device 12 may be adjusted about the axis of the shaft 16 relatively to the path of movement of the driver 10. The arm 60 is provided with an arcuate slot 62 which is concentric to the axis of the shaft 56 through which passes a screw 64 threaded into the bracket 58 to clamp the arm 60 and the eccentric 54 in fixed position. A second arm 66 of the bell crank lever 52 extends upwardly and is pivotally connected to one end of a link 68 which extends to the left and which at its other end is pivotally connected to the lower end of a cam lever 70. The cam lever 70 is pivoted to a horizontal shaft 72 extending forwardly and rearwardly of the machine which is

secured in a bracket 74 to the machine by a threaded stud 75. The cam lever 70 carries a cam roll 76 which enters a cam groove, the center line 77 of which is shown by a dot and dash line in Fig. 1, in the rear face of a cam 78 secured to the drive shaft 80 of the machine. The cam 78 operates the shearing and transferring device 14 through the mechanism above described.

The shearing and transferring device 12 is actuated solely by levers and links including the two toggles referred to above, one toggle comprising the arm 26 and the link 24 which is in straightened condition when the shearing and transferring device 12 is in shearing position. The other toggle comprises the link 48 and the arm of the bell crank lever 52 which is in straightened condition when the shearing device 12 is in fastening inserting position. After the wire has been fed into the passage 37 in the shearing and transferring device 12, the cam lever 70 is rotated in a clockwise direction. The bell crank lever 52 is rotated in a counterclockwise direction thereby swinging the link 48 and the arm of the bell crank lever 52 connected thereto into the straight line position shown in dotted lines in Fig. 1. At the same time the link 24 and the arm 26 of the bell crank lever 28 have been moved from the straight line position to the position shown in dotted lines in Fig. 1. During the first portion of the movement of the shearing and transferring device 12 the wire is severed and during the remainder of the portion of the movement of the device 12 the severed fastening is moved into driving position. The passage 37 in fastening receiving position having been properly alined with the passage 39 by means of the eccentric adjusting the mechanism 30 described above and the position of the passage 37 having also been adjusted through the eccentric mechanism on which the bell crank lever 52 is mounted, the passage 37 will be properly alined in both its fastening receiving position and fastening driving position. The position of the device 12 cannot be changed in either fastening receiving or fastening inserting position because of the straightened condition of one of the pairs of toggles in each of the above positions. The device 12, therefore, is held positively against movement when the wire is being fed into the device 12 and the device is also positively held against movement when a fastening is being driven. Furthermore, the device 12 is readily adjustable about its axis in either position by means of the eccentric sleeve 30 and the eccentric shaft 54.

Having thus described our invention, what we claim as new and desire to secure by Letters Patent of the United States is:

1. In a fastening forming and inserting machine, a pair of dies movable relatively to each other to sever a fastening from a length of fastening material, one of said dies being also movable to transfer the severed fastening to inserting position, and mechanism including a plurality of toggles operative to cause relative movement between said dies, said toggles being constructed and arranged to hold said dies positively against movement relatively to each other prior to the severing operation and to hold the transferring die positively against movement after it has been moved to inserting position.

2. In a fastening forming and inserting machine, a pair of dies movable relatively to each other to sever a fastening from a length of fastening material, one of said dies being also movable to transfer the severed fastening to insert-

ing position, and mechanism including a plurality of links for causing relative movement between said dies, a pair of said links being constructed and arranged for movement into the form of a straightened toggle to hold said dies positively against movement relatively to each other during the severing operation, and another pair of links arranged for movement into the form of a straightened toggle to hold the transferring die positively against movement after it has been moved to inserting position.

3. In a fastening forming and inserting machine, a pair of dies having relative movement to shear off and present a fastening, and mechanism constructed and arranged to effect relative movement of one of said dies, said mechanism including a pair of toggles one of which is movable into straightened condition to hold the dies positively against movement relatively to each other prior to the shearing operation and the other of which is movable into straightened condition to hold the die positively against movement after it has been moved to inserting position.

4. In a fastening forming and inserting machine, fastening inserting means, a relatively fixed die, a die arranged for rotation to sever a fastening and by continued movement in the same direction to present the fastening in driving position, and mechanism arranged to rotate the said die, said mechanism including a plurality of links, a pair of said links being movable into straightened condition to hold the rotatable die positively against movement relatively to the fixed die prior to the severing operation, and another pair of said links movable into straightened condition after the fastening has been severed and delivered in driving position to hold said die positively against movement relatively to the fastening inserting means.

5. In a fastening forming and inserting machine, fastening receiving means arranged for rotation to sever a fastening and by continued movement in the same direction to present the fastening in driving position, and mechanism for rotating the fastening receiving means, including a pair of toggles one of which is movable into straightened condition prior to the severing operation and the other toggle being movable into straightened condition during the driving operation.

6. In a fastening forming and inserting machine, a die, a die carrier arranged for rotation to move the die from a horizontal fastening receiving position to a vertical fastening driving position, an arm on the carrier, a cam, and a plurality of links connecting said arm to said cam, said links being arranged in the form of a pair of toggles one of which is movable into straightened condition while the die is in fastening receiving position and the other of which is movable into straightened condition during the fastening driving operation.

7. In a fastening forming and inserting machine, a stationary die, a shearing and transferring die co-operating with the stationary die and movable from fastening receiving position to sever a fastening from a length of fastening material and to transfer the severed fastening to driving position, a link connected to said shearing die, a bell crank lever having one arm connected to said link, means for adjusting said bell crank lever to position the co-operating die relatively to the stationary die, a link secured to the other arm of the bell crank lever, a second bell

crank lever having an arm secured to said second link, means for adjusting said second bell crank lever to position the shearing die in driving position, and means connected to the other arm of the second bell crank lever for moving the shearing and transferring die from a fastening receiving position to fastening driving position.

8. In a fastening forming and inserting machine, a stationary die, a shearing and transferring die co-operating with the stationary die and movable from fastening receiving position to sever a fastening from fastening material and to transfer the fastening to driving position, and mechanism constructed and arranged to move said shearing and transferring die, said mechanism including a link connected to the shearing die, a bell crank lever having one arm connected to said link, said link and said arm being arranged in a straight line when the shearing die is in fastening receiving position, means on which said bell crank lever is mounted for adjusting the position of the shearing die relatively to the stationary die, a second bell crank lever having an arm connected to the other end of said second-mentioned link, said arm of said second bell crank lever and said second link being arranged in a straight line when the shearing die is in driving position, and means on which the second bell crank lever is mounted for adjusting the said arm and link to position the shearing die in driving position.

9. In a fastening forming and inserting machine, a die, a die carrier arranged for rotation to move the die carrier from a substantially horizontal fastening receiving position to a substantially vertical fastening driving position, a link connected at one end to said carrier, a bell crank lever having one arm connected to the other end of said link, said link and said arm being arranged in a straight line when the die is in fastening receiving position, a second link connected to the other arm of said bell crank lever, a second bell crank lever having an arm connected to the other end of said last-mentioned link, said second link and the arm of said second bell crank lever being arranged in a straight line when the die carrier is in driving position, a link connected to the other arm of said second bell crank lever, and means connected to the other end of said last-mentioned link for imparting fastening severing and transferring movement to said die carrier through said means and said link and lever.

10. In a fastening forming and inserting machine, a movable die, a co-operating die, a die carrier arranged for rotation to move the movable die from a substantially horizontal fastening receiving position to a substantially vertical fastening driving position, a link connected at one end to said carrier, a bell crank lever having one arm pivotally connected to the other end of said link, said link and said arm being arranged in a straight line when the movable die is in fastening receiving position, means on which the bell crank lever is pivotally secured for adjusting the position of the movable die relatively to the co-operating die, a second link connected to the other arm of said bell crank lever, a second bell crank lever having an arm connected to the other end of the second link, said second link and the arm of the second bell crank lever being arranged in a straight line when the die carrier is in driving position, a link connected to the other arm of said second bell crank lever, and means connected to the other end of said last-mentioned link for imparting fastening severing and transferring move-

ment to said die carrier through said links and lever.

11. In a fastening forming and inserting machine, a die, a die carrier arranged for rotation to move the die from a substantially horizontal fastening receiving position to a substantially vertical fastening driving position, a link connected at one end to said carrier, a bell crank lever having one arm connected to the other end of said link, said link and said arm being arranged in a straight line when the movable die is in fastening receiving position, thereby holding the die against movement when the die is in said position, a second link connected to the other arm of said bell crank lever, a second bell crank lever having an arm connected to the other end of the second link, said second link and the arm of said second bell crank lever being arranged in a straight line when the die carrier is in vertical driving position, thereby holding the die against movement when the die is in said position, means on which the second bell crank lever is pivotally mounted, said means being adjustable to position the die in vertical driving position when said second link and the arm of said second bell crank lever are in straightened position, a link connected to the other arm of said second bell crank lever, and means connected to the other end of said last-mentioned link for imparting fastening severing and transferring movement to said die carrier through said links and levers.

12. In a fastening forming and inserting machine, a die, a die carrier arranged for rotation to move the die from a substantially horizontal fastening receiving position to a substantially vertical fastening driving position, a link connected at one end to said carrier, a bell crank lever having one arm connected to the other end of said link, said link and said arm being arranged in a straight line when the movable die is in fastening receiving position, thereby holding the die against movement when the die is in said position, a second link connected to the other arm of said bell crank lever, a second bell crank lever having an arm connected to the other end of the second link, said second link and the arm of said second bell crank lever being arranged in a straight line when the die carrier is in vertical driving position, thereby holding the die against movement when the die is in said position, means on which the second bell crank lever is pivotally mounted, said means being adjustable to position the die in vertical driving position when said second link and the arm of said second bell crank lever are in straightened position, a link connected to the other arm of said second bell crank lever, and means connected to the other end of said last-mentioned link for imparting fastening severing and transferring movement to said die carrier through said links and levers.

chine, a movable die, a stationary co-operating die, a die carrier arranged for rotation to move the movable die from a horizontal fastening receiving position to a vertical fastening driving position, a link connected at one end to said carrier, a bell crank lever having one arm connected to the other end of said link, said link and said arm being arranged in a straight line when the movable die is in fastening receiving position, thereby holding the die against movement when the die is in said position, means on which said bell crank lever is positioned, constructed and arranged to position the movable die in fastening receiving position when said link and said arm are in straightened condition, a second link connected to the other arm of said bell crank lever, a second bell crank lever having an arm connected to the other end of said second link, said second link and the arm of the second bell crank lever being arranged in a straight line when the die carrier is in driving position, thereby holding the die against movement when the die is in said position, means constructed and arranged to be adjusted to locate the die in driving position when said second link and said arm of the second bell crank lever are in straightened condition, and means connected to the other end of said last-mentioned link for imparting fastening severing and transferring movement to said die carrier through said links and levers.
